Application August 20, 1932, Serial No. 629,622

14 Claims. (Cl. 103—271)

The present invention relates to injectors and has particular reference to injectors intended to be operated primarily by exhaust steam from an engine and hereinafter referred to as exhaust steam injectors.

The primary purpose of using exhaust steam injectors is to improve fuel economy by returning to the boiler, in the form of heated feed water, the heat of a portion of the steam exhausted from the engine operating on steam from the boiler, which heat would otherwise be lost. In order to recover and return to the boiler the largest amount of heat from the exhaust steam, it is desirable to condense in the injector as large a quantity of exhaust steam as possible. The amount of exhaust steam which can be condensed in an exhaust steam injector is dependent, among other things, upon the amount of water being fed to the injector and the amount of water fed to the injector will usually vary considerably, particularly when the injector is employed for feeding water to a locomotive boiler.

Due to the relatively great difference in pressure between the pressure of the exhaust steam employed and the boiler pressure against which the injector must deliver, exhaust steam injectors are considerably more sensitive in operation than are live steam injectors and the sensitivity of the injector becomes increasingly great as the water regulation approaches the minimum capacity of the injector or the maximum capacity of the injector. In general, however, it may be said that the greater the rate at which water is fed to the injector, the greater is the rate at which exhaust steam can be condensed without endangering stability of operation.

In the prior development of exhaust steam injectors it has been found that improved results can be obtained by condensing what may be termed a primary supply of exhaust steam with the water fed to the injector and by thereafter condensing a secondary supply of exhaust steam with the mixture of feed water and condensate of primary steam before the mixture enters the combining tube of the injector. In connection with our development of exhaust steam injectors we have found that the performance of exhaust steam injectors of the above character can be improved in a manner hereinafter to be more fully pointed out, due to a characteristic of said injectors which we believe has not heretofore been appreciated. It is our conclusion that in injectors where primary and secondary steam supplies are employed in

the formation of a single jet, the major portion of the energy of the steam in the primary supply is converted into energy of velocity, giving velocity to the mixture entering the combining tube of the injector, whereas the major portion of the energy of the secondary steam is recovered as heat energy tending to raise the temperature of the liquid delivered by the injector.

In accordance with the present invention we utilize this characteristic to raise the temperature of the liquid delivered from the injector to the maximum practical degree while at the same time not impairing the stability of the injector or its range of capacity by throttling under any conditions of injector operation the area of the nozzle orifice through which the primary steam supply flows.

The more specific nature of the invention and the several objects and advantages thereof will appear more fully in conjunction with the ensuing description of the apparatus suitable for carrying the invention into effect which is illustrated in the accompanying drawing forming a part of this specification.

In the drawing:

Fig. 1 is a longitudinal central section of an exhaust steam injector embodying the invention;

Fig. 2 is a plan view of a part of the injector shown in Fig. 1, and

Fig. 3 is a section of part of an injector showing a different primary steam nozzle arrangement.

Turning now to Fig. 1, the injector illustrated is of the so-called Metcalfe type and is adapted to operate on live steam at low pressure, hereinafter referred to as auxiliary steam, when exhaust steam is not available and is also adapted to employ a relatively small amount of high pressure live steam hereinafter referred to as supplementary steam. It is distinctly understood, however, that the invention is not limited to this particular type of injector, which has been chosen for purposes of illustration, but is equally applicable to other types of injectors as well.

In Fig. 1 the injector body is indicated generally at 10 and comprises a main low pressure steam chamber 11 to which exhaust steam is admitted through the inlet 12 controlled by exhaust valve 13. Valve 13 is closed by spring 14 and is adapted to be opened by pressure of steam admitted through channel 15 to piston 16. When exhaust steam is not available auxiliary live steam may be admitted to chamber 55

11 by way of chamber 17 and ports 18 and supplementary live steam is admitted by way of chamber 19 and the supplementary steam nozzle 20.

- 5 Water is admitted to chamber 21 of the injector through inlet 22 and the primary nozzle member 23, fixed in casing 10, projects through chamber 21 so as to deliver primary steam at a point within the water nozzle forming member 10
 10 24. For purposes of the present application, we will employ the term "nozzle" to designate the opening or space through which fluid passes rather than the member or members the walls of which define such opening. Thus, the nozzle member 23 provides a main or primary steam nozzle 25 and the water nozzle 26 is formed between the walls of member 24 and the walls of the sleeve or shroud 27 which is slidably mounted within the casing and axially movable 15
 15 to vary the area of nozzle 26 in order to control the amount of water supplied to the injector. 20

In the device illustrated, axial movement of shroud 27 is effected by turning spindle 28 which is mounted in the casing and which carries at 25 its lower end an eccentrically mounted pin 29 engaging a suitable slot in shroud 27. Turning movement of spindle 28 is effected through the medium of the external control handle 30 which is adapted to be actuated through any suitable 30 linkage, not shown. Advantageously, equalization of water pressure in the spaces adjacent to the shroud 27 is ensured as by the provision of one or more ports 31 in the shroud and a groove 31 in nozzle 23.

- 35 Turning now for a moment to Fig. 3, there is illustrated another arrangement in which the shroud 27' is fixed in the casing and the primary nozzle member 23' is slidably mounted and engaged by pin 29 to effect variation in the area 40 of the opening of water nozzle 26.

A secondary steam supply chamber 31 in the injector is connected with the main low pressure chamber 11 by means of conduit 32 which may advantageously be formed within the casting of the injector and slidably mounted within the casing adjacent to chamber 31 is the secondary steam nozzle member 33. As will be evident from the drawing, the walls of members 24 and 33 form an annular secondary steam nozzle 34 the area of which may be varied by movement of member 33. Movement of member 33 may advantageously be effected by an arrangement such as the one illustrated comprising an operating spindle 35 similar to spindle 28 and carrying an eccentric pin 36 engaging a slot in member 33. Spindle 35 is actuated by handle 37 and the handles 30 and 37 are connected by the link 38 pivotally secured to the handles by pins 39 and 40. Intermediate its 45 ends the link 38 is provided with a hole 41 adapted to register with a hole 42 in the fixed arm 43 when the link is in the position shown in Fig. 2.

At the discharge side of nozzle member 33 are located the usual combining and delivery tubes 44 and 45, respectively, the outlet end of 65 the latter being in communication with the delivery pipe 46 through the usual check valve 47 and the combining chamber 48 being in communication with the usual overflow passage 49.

70 Operation of the apparatus is as follows:

Low pressure steam from chamber 11 is delivered through the primary steam nozzle 25 and water is delivered through the water nozzle 26, the quantity of water delivered being regulated 75

by the axial position of the water nozzle forming member which, in the form shown in Fig. 1, is shroud 27 and in the form shown in Fig. 3 is the primary steam nozzle member. Additional low pressure steam from the supply admitted to chamber 11 is condensed at the secondary steam nozzle 34, the size of which is governed by the position of member 33. By reference to Fig. 2, it will be evident that if regulation of the amount of water supplied to the injector is effected by moving handle 30 in clockwise direction the shroud 27 will be moved to the left in Fig. 1, thereby decreasing the area of the water nozzle 26. At the same time, handle 37 will be moved in counter-clockwise direction 15 and member 33 will be moved to the right in Fig. 1, thus decreasing the area of nozzle 34. In the drawings the above parts are shown in the position giving minimum water nozzle opening and secondary steam nozzle opening. 20

It is evident that when the minimum amount of water is supplied to the injector, the injector has the minimum capacity for condensing steam and consequently the total area of the nozzles supplying steam to the injector should correspond to the requirements of the injector under conditions of minimum water supply. However, under conditions of minimum water supply, the injector will usually still have to deliver against the usual delivery pressure and the supply of primary steam should, therefore, be not reduced, in order that the full kinetic effect of this steam may be availed of. 30

As the amount of water fed to the injector increases, the capacity of the injector to condense steam also increases and in accordance with the present invention this increased capacity of the injector to condense more steam is availed of by increasing the amount of secondary or heating steam supplied to the injector, and the increase (or decrease in the case of a diminishing water supply) is effected by changing the secondary nozzle area so as to avoid the losses which would occur if the secondary steam supply were throttled prior to admission to the 45 secondary steam chamber. 40

By the arrangement which we have provided it is possible to secure maximum steam condensing capacity, and consequent maximum fuel economy, through regulation of the area of the 50 secondary steam nozzle, whereby the maximum quantity of exhaust steam is condensed which can be condensed with any given amount of water. At the same time, stability of operation of the injector throughout its capacity range is 55 maintained as is also the ability of the injector to deliver against its normal delivery pressure under different conditions, because of the relatively fixed character of the primary steam nozzle. 60

It will be evident that the capacity of the injector to condense steam is a function not only of the quantity of water fed to the injector but also of the temperature of the water. The lower the temperature of the water the greater is the 65 capacity of the injector to condense steam. In the case of injectors applied to locomotives, particularly in certain geographical locations, the temperature of the water supplied to the injector will vary between wide limits at different 70 seasons of the year. In many cases, for example, the temperature of the water supplied to the injector during two or three summer months is relatively high and if the injector is designed with nozzle openings so that during 75

the major portion of the time the maximum steam condensation and consequent economy is obtained, there will be certain periods when operation of the injector will tend to become unstable because of the high temperature of the water fed to the injector. Desirable as is the factor of maximum fuel economy, dependability of operation is still more important and in order to avoid any possible difficulty due to instability of operation because of too large a steam nozzle area, the secondary steam nozzle may be kept at minimum opening by removing the pivot pin joining link 38 with the handle 30 and inserting this pin through the hole 42 in the arm 43 and hole 41 in link 38, thus locking member 33 in a position giving minimum secondary steam nozzle opening. This operation is extremely simple and may be effected without in any way disturbing the connections to the injector or any of its interior parts. Furthermore, with this arrangement injectors may be built according to a more or less standardized design and still be applicable under widely varying service conditions. In some localities the adjustability of the secondary steam nozzle in accordance with water regulation may be utilized at all times and in other localities where the water supply is at times at excessive temperatures, the benefits to be derived from the adjustable secondary steam nozzle may be obtained during the seasons when a water supply at relatively normal temperature is available, without sacrificing stability of operation at times when high water supply temperatures are encountered.

It will be appreciated by those skilled in the art that in many instances the exhaust steam supplied to an injector is not only pulsating in character but varies considerably in average pressure. Exhaust steam injectors operate to the best advantage with steam at relatively constant pressure and frequently pressure regulating means are employed in the conduit through which exhaust steam is supplied from the engine to the low pressure steam chamber or chambers of the injector. In this connection we wish it to be understood that the term "fixed" and other like terms employed herein to indicate a fixed primary steam supply are to be interpreted so as to include steam supplies having the normal variations in pressure and quantity of steam as exhausted from an engine or as discharged from a regulating valve from which the steam is conducted to the injector.

Within the scope of the invention many changes and variations in the form of apparatus employed may be made, and certain features of the invention may be employed to the exclusion of others.

What is claimed is:

1. In an injector, means providing a main steam nozzle, means providing a water nozzle of variable area arranged to deliver water for condensing steam from said main nozzle to establish a jet and means providing a secondary steam nozzle for supplying additional steam to be condensed by the jet of water and condensate established by the main nozzle and the water nozzle, said last mentioned means comprising a movable nozzle member for varying the area of said secondary nozzle in accordance with variations in the area of said water nozzle.

2. In an injector, means providing a main steam nozzle of fixed area, a casing, means comprising a nozzle member movable in said casing

to provide a water nozzle of variable area arranged to deliver water for condensing steam from said main nozzle to establish a jet, means comprising a nozzle member movable in said casing to provide a secondary steam nozzle of variable area for supplying additional steam to be condensed by the jet of water and condensate established by the main nozzle and the water nozzle and means operatively connecting said nozzle members to cause simultaneous increase or decrease in the areas of said water nozzle and said secondary steam nozzle upon movement of the first mentioned member.

3. In an injector, a casing providing a steam chamber for low pressure steam, means in said casing providing a main steam nozzle of fixed area in communication with said chamber, means in said casing comprising a movable nozzle member for providing a water nozzle of variable area arranged to deliver water for condensing steam from said main nozzle to establish a jet, means for moving said member to vary the amount of water supplied to the injector, means comprising an annular nozzle member movable in said casing for providing a secondary steam nozzle, for supplying additional steam to be condensed by the jet of water and condensate established by the main nozzle and the water nozzle, a conduit providing an unrestricted path of flow for low pressure steam as supplied to the injector to said secondary nozzle, and means operatively connecting said movable members for causing the area of the secondary steam nozzle to vary in predetermined relation with respect to variations in area of the water nozzle.

4. In an injector, a casing providing a low pressure steam chamber, a plurality of nozzle forming members mounted in axial alignment in said casing to form in the order named a main steam nozzle in communication with said chamber, a water nozzle and a secondary steam nozzle for supplying additional steam to be condensed by the jet of water and condensate from the main nozzle and the water nozzle, a plurality of said members being movable with respect to the other members to vary the area of said water nozzle and of said secondary steam nozzle and means for operatively connecting the members movable to determine the size of the two last mentioned nozzles, said secondary steam nozzle being in communication with a source of low pressure steam as supplied to the injector.

5. In an injector, a casing providing a low pressure steam chamber, a plurality of nozzle forming members mounted in axial alignment in said casing to form in the order named a main steam nozzle in communication with said chamber, a water nozzle and a secondary steam nozzle, said members comprising a water nozzle forming member fixed in said casing and a plurality of members movably mounted in said casing adjacent to the fixed member to form a water nozzle and a secondary steam nozzle having variable areas, said movable members being interconnected and said secondary steam nozzle being in communication with a source of low pressure steam as supplied to the injector and supplying additional steam to be condensed by the jet of water and condensate established by the main nozzle and the water nozzle.

6. In an injector having a water nozzle and a secondary steam nozzle, a member movable to vary the area of said water nozzle, a second member movable to vary the area of said secondary steam nozzle, actuating means for mov-

ing said first member, actuating means for moving said second member and means for alternatively connecting said last mentioned means to said first mentioned means or to a fixed part 5 of the injector to lock said second member in a position providing minimum opening of said secondary steam nozzle.

7. In an injector, a casing providing a low pressure steam chamber, a member fixed in said 10 casing and providing a primary steam nozzle of fixed area in communication with said chamber, a second member fixed in said casing, a shroud movably mounted in said casing around the first mentioned member and cooperating with the 15 second mentioned member to provide a water nozzle of variable area, a third member slidably mounted in said casing and cooperating with the second mentioned member to provide a secondary steam nozzle of variable area and means for 20 operatively connecting said shroud and said third member whereby to cause simultaneous enlargement or contraction of the areas of said water and secondary steam nozzles, said secondary steam nozzle being in communication 25 with said low pressure steam chamber.

8. In an injector, a casing providing a low pressure steam chamber, a member slidably mounted in said casing adjacent to said chamber and providing a main steam nozzle, a second 30 member fixed in said casing adjacent to the first member and cooperating therewith to form a water nozzle of variable area, a third member slidably mounted in said casing adjacent to said second member and cooperating therewith to form a secondary steam nozzle of variable area located to supply additional steam 35 from said chamber to be condensed by the jet of water and condensate established by the main nozzle and the water nozzle and means 40 operatively connecting said first member and said third member to cause simultaneous enlargement or contraction of said water nozzle and said secondary steam nozzle, said secondary steam nozzle being in communication with said 45 low pressure steam chamber.

9. In the operation of an exhaust steam injector of the type in which a main steam supply is combined with a water supply to establish a jet and a secondary steam supply is condensed by said jet to increase the temperature of the jet, that improvement which consists in maintaining a constant main steam supply and varying the quantity of secondary steam in accordance with variations in the quantity of water 50 supplied to the injector.

10. In an injector, the improved method of forming a jet of variable quantity which consists in establishing a central jet of primary steam of constant area, condensing said jet of steam with

an annular envelope of water, varying the quantity of water supplied by varying the thickness of said envelope, condensing secondary steam by admitting an annular envelope of secondary steam around the jet formed by the water and the primary steam and varying the amount of secondary steam condensed by varying the thickness of the envelope of secondary steam in accordance with variations in the thickness of the envelope of water. 10

11. In an injector, a casing, a water nozzle forming member in said casing and a plurality of members in said casing and movable with respect to the first mentioned member and cooperating therewith to form a water nozzle and a secondary steam nozzle on opposite sides of the first mentioned member, said last mentioned members being interconnected for simultaneous enlargement or contraction of the areas of said nozzles. 15

12. In an injector, a casing, a water nozzle forming member in said casing and a plurality of members in said casing movable with respect to said first mentioned member and cooperating therewith to form a water nozzle and a secondary steam nozzle on opposite sides of the first mentioned member, said last mentioned members being interconnected for simultaneous movement toward and away from said first mentioned member. 20

13. In an injector, a casing, a water nozzle forming member fixed in said casing, a first movable member in said casing to one side of the first mentioned member and cooperating therewith to form a water nozzle, a second movable member in said casing on the opposite side of the first mentioned member and cooperating therewith to form a secondary steam nozzle and means interconnecting said movable members for causing simultaneous movement thereof toward or away from each other. 30

14. In an injector, a casing, means in said casing forming a primary steam nozzle, a water nozzle and a secondary steam nozzle comprising a first member movable to vary the area 45 of the water nozzle and a second member movable to vary the area of the secondary steam nozzle, a spindle operable to move the first mentioned member, a spindle operable to move the second mentioned member, an arm on each of 50 said spindles, a link connecting said arms, said link being disconnectable from the arm on the first mentioned spindle and means cooperating with said casing for fixing the link in a position corresponding to minimum area of said 55 secondary steam nozzle.
